REFINING SUGAR

Pedro Sanchez, Buffalo, N. Y.

No Drawing. Application April 9, 1934,
Serial No. 719,899

10 Claims. (CL 127—48)

The present invention relates to a method of refining sugar and more particularly to a method of treating raw sugar contained in the juice expressed from sugar cane and sugar beet and other saccharin forming plants whereby solutions, syrups and the like containing such sugars may be clarified and decolorized.

- In the purification and production of substantially pure sugar, the sugar going to the refineries 10 is obtained from crystallization of the juices expressed from the cane, beet and the like. The sugar crystals are coated with a film of molasses, this type of sugar being generally designated as "raw sugar".
- 15 In the refining operations generally practiced prior to this invention, this raw sugar is cold mixed with water or with raw sugar washings, from previous operations to form a heavy magma. This magma is then purged in centrifugal machines; after the syrup has been spun off, the sugar in the centrifugal baskets is sprayed with water to eliminate as much as possible of the adhering molasses. The sugar obtained by this treatment, so-called affinated or washed sugar, is 20 further refined and the generally accepted practice heretofore has been to prepare a heavy solution of sugar and water of a sugar content of about 55° Brix, such solutions possessing undesirable color, colloids, waxes, etc., and in addition 25 possessing a certain content of invert sugar, as well as mineral matter designated as ash.

In order to reduce the degree of color in this syrup or sugar solution this solution is often treated with lime and phosphoric acid or phosphates at raised temperatures in order to render the solution suitable for clarification or filtration. This "clarified" or filtered solution is then decolorized by treating with an "activated" carbon at 30 160 to 180° F., the solution generally being treated 35 with a portion of carbon having already been used once before for this purpose, filtered and thereafter treated with a fresh portion of activated carbon; this latter upon being filtered from the solution is used with a fresh batch of 40 the syrup. In some cases, this activated carbon 45 can be regenerated, its decolorizing properties restored and used again in the process. Another widespread method of decolorizing the solution is to pass the solution at temperatures generally 50 above 160° F., as is the case when treating with activated carbon, through so-called "bone char" filters. The solution or syrup is generally passed repeatedly through the bone char filter, the number of passages depending upon the amount of 55 color to be removed. The efficiency of the bone

char as a decolorizing agent progressively decreases with use and in order to restore the activity of the bone char it must be revivified by heating to high temperatures out of contact of air.

In the processes used heretofore large amounts of energy are consumed in maintaining the sugar solution or syrup at elevated temperatures of above 160° F. at this temperature an increase in invert sugars is unavoidable, thus reducing the 10 purity of this solution and, therefore, diminishing the yield of crystallized sugar.

In case of the bone char process large amounts of char have to be used in order to obtain the desired decoloration, the amount of char being 15 at least 60%, and in some cases as high as 100%, based on the weight of sugar treated. There will be always a large amount of bone char and sugar liquor in operation. For this reason a large investment is required in plant and char 20 equipment, as well as in char including the char in process and in the regenerating units.

The wash water consumption is very great; a large quantity of hot water being necessary for the washing of the char filters to remove from 25 the char the absorbed sugar solution to reduce to a minimum the loss in sucrose. Due to all these facts maintenance, labor, fuel and depreciation on investment are comparatively high.

In case of the use of the activated carbon 30 process, the quantities of activated carbons used are considerably smaller, however, if a revivable carbon is used, the revivifying losses are much greater than in case of bone char, and due to the fact that non-sugars are not eliminated 35 with these carbons and that invert sugar is increased, the purity of the decolorized solution and, therefore, the yield of the crystallized sugar is always appreciably lower. The cost of filtrations is comparatively high, as solutions must be filtered at least twice and in most cases special filtering equipment has to be used. The filtration 40 sometimes causes difficulties on account of the fineness of the activated carbon which easily passes through the filter cloth.

The present invention provides a method of refining affinated or washed sugar solutions which eliminates certain of the steps heretofore used while at the same time a quality grade of 45 pure refined sugar is produced. The present 50 process also provides a method for refining sugar at temperatures normally encountered in climates or localities wherein sugar is refined without the necessity of maintaining the sugar syrups or solutions at temperatures far in excess of the 55

temperatures prevailing in that locality; that is, at room temperature and usually less than 120° F. The present invention further provides a method of refining sugar wherein the sugar may be clarified, decolorized and filtered in substantially one operation, producing a syrup that may be immediately grained in the vacuum pan or used without further treatment as refined sugar syrup. The invention also provides a method 10 of purification wherein the amount of invert sugar originally present may be substantially reduced and whereby the adverse effect of the invert sugar upon the crystallization of sucrose is diminished.

15 In practicing the improved refining procedures of my invention, raw sugar, as obtained on crystallization from the juice, is treated in the usual way and affinated or washed sugar obtained. This sugar is dissolved in water to obtain syrups 20 having a specific gravity as high as 1.35 or 70° Brix. The resulting solutions or syrups possess the characteristic light yellow to brownish color due to coloring impurities retained by the affinated or washed sugar, to certain waxes, gums, 25 colloidal impurities as well as small particles of non-sugar. According to my process this syrup can be clarified, decolorized and filtered in one operation to produce a clear, sparkling water white syrup which may be used as such or from 30 which the sugar may be crystallized as pure white refined sugar. By this process the lengthy, laborious and costly decolorizing and filtering processes currently in use are eliminated.

To effect this purification and refining, the 35 sugar solution is treated with chlorine in an active state, that is a state wherein the chlorine possesses the property of oxidizing or destroying, or otherwise rendering colorless, the color imparting constituents of the syrup while at the 40 same time an insoluble material is formed within the syrup that, moving through the body of the syrup in a flocculent form and a form exposing a large surface of contact to the syrup, collects and retains certain colloid matters and 45 deleterious non-sugar materials.

The term "chlorine in the active condition", refers to that type of chlorine which possess the ability to react upon colored materials changing such materials to uncolored substances and 50 includes the substances generated when gaseous chlorine is absorbed by water which may contain acids or alkalis. Certain of these substances containing active chlorine are also obtainable in powder form and fall generally into two classes, 55 those possessing a high chlorine content, in the neighborhood of 60 to 70% available or active chlorine and those possessing up to about 40% active or available chlorine. The most suitable substances containing active chlorine are those 60 whose metal ions are able to form materials insoluble in sugar solution, for instance calcium, magnesium, barium, strontium, aluminum and other hypochlorites when treated with the proper materials cooperating in the obtainment of the 65 effect desired.

Substances suitable for producing flocculent and insoluble precipitate with the substance containing the active chlorine within the syrup comprise acids and acid salts capable of forming 70 substances insoluble in the syrup which at the same time remove ash forming mineral matter by combining chemically therewith, as for instance, phosphoric acid, salts of phosphoric acid, such as mono calcium phosphate, oxalates and 75 borates and in general comprise acids or acid

salts which form a precipitate substantially insoluble in sugar solution.

By way of example a 63° Brix syrup of affinated sugar is agitated at room temperature with sufficient calcium hypochlorite or bleaching powder 5 to give about one tenth of one percent of active chlorine based upon the weight of actual sugar treated, although this quantity of material is illustrative only as the quantity to be used will depend upon the sugar used, and sufficient mono calcium 10 phosphate, in finely divided form, mixed and agitated with the syrup to produce a flocculent precipitate of tricalcium phosphate, precipitating substantially all of the metallic ion added in the bleaching powder and at the same time in an 15 amount sufficient to impart the desired hydrogen ion concentration to the syrup. Under thorough agitation of the syrup with the chemical reagents the active chlorine chemically decolorizes the color imparting materials in the solution while 20 at the same time very finely distributed gas is liberated, collects upon and adheres to the small particles of flocculent precipitate so that upon cessation of agitation of the syrup the buoyant effect of such liberated gas causes all the flocculent 25 insoluble matter to rise upwardly through the solution and collect as a scum upon the top thereof of leaving the subnatent liquor or syrup clear, sparkling and substantially water white, the color depending on the amount of active chlorine used, 30 with a layer of insoluble scum upon the surface thereof the quantity of which represents about one eighth to about one twentieth of the total volume of material.

The time required for a complete clarification 35 depends to a large extent on the quality of the sugar treated and may vary from one half to ten hours. In plants not having enough capacity in regard to settling tanks, it may be advisable to filter the entire solution together with the precipitate, which acts as filtering medium, according to 40 any of the known methods, as soon as the desired decolorization is obtained. In any case it is advisable to incorporate a filtering aid.

This clarifying and decolorizing step having 45 been performed in suitable settling tanks provided with draw-off means adjacent the bottom thereof, the subnatent syrup is separated from the insoluble matter and subsequently treated as will be hereafter more fully described while the insoluble matter is conveyed by suitable pumping or other conveying means and filtered to remove the syrup admixed therewith, the filtrate being added to the bulk of clarified and decolorized syrup for subsequent treatment.

It is found that if this treatment with hypochlorite be performed in slightly alkaline solution, oxidation of invert sugar is induced thus reducing the content of the invert sugar in the syrup. The formation of colored compounds is 60 entirely avoided as the operation is performed at room temperature.

It has been found advisable that the last traces of active chlorine present in the solution, and that portion of active chlorine not consumed in chemical action or decolorization, be removed. To this end, any suitable dechlorination treatment may be used and in general substances possessing the faculty of destroying hypochlorites and active chlorine not at the same time increasing the ash 70 content or adding mineral matter to the syrup are desirable. Hydrogen peroxide possesses these characteristics and is added in an amount sufficient to destroy the active chlorine and compounds formed with it, although other substances 75

or other modes of procedure may be used to effect this result. Thus, where bone black filters are already installed, the clarified and decolorized solutions may be passed through the bone char 5 and dechlorinated while at the same time a small amount of mineral matter is removed from the syrups.

It will be seen from the foregoing that the present invention provides a method of refining 10 sugar that requires a minimum of apparatus, effects considerable saving in consumption of energy since the operation may be effected at room temperatures and eliminates many of the steps currently used in obtaining refined sugar. 15 since by the procedures of the present invention the steps of clarifying the solution, decolorizing the solution and filtering the solution may be performed at the same time due to the fact that the insoluble matter produced by the interaction 20 of the substance bearing the active chlorine and an acid or acid salt is formed in such manner as to possess a large surface disposed to the action of the solution at which surface gas is formed due to decomposition of the constituents 25 bearing the active chlorine, such as a hypochlorite, which gas moves the insoluble flocculate upwardly through the solution collecting the colloidally dispersed matter, removing coloring matter and collecting upon the top of the solution 30 as a scum which may be readily removed and filtered in any convenient fashion while the subnatent liquid has been clarified, decolorized and filtered, although certain cases may arise where it is advantageous to filter the liquid.

35 The term "substantially decolorize" as used in the claims, means color elimination producing (a) a substantially water white solution, or (b) a solution having so much of the original color removed as to permit the utilization of the solution for crystallization of white granulated sugar therefrom or as a syrup, or (c) a removal of a major amount of the color where the remaining color may, if desired, be removed by physical or mechanical means, as for instance, by carbon 40 or by other methods.

5 What is claimed is:

1. The method of decolorizing affinited sugar which consists in treating the syrup made from the affinited sugar with a quantity of a hypochlorite sufficient to substantially decolorize the solution.

2. The method of decolorizing affinited sugar which consists in treating the syrup made from the affinited sugar at room temperature with a quantity of a hypochlorite sufficient to substantially decolorize the solution at room temperature.

3. The step in the method of refining affinited sugar which comprises substantially decolorizing the syrup made from the affinited sugar by means of a hypochlorite.

4. The method of refining affinited sugar 5 which comprises substantially decolorizing the syrup made from the affinited sugar by means of a quantity of a hypochlorite sufficient to substantially decolorize the solution and a quantity of material of the group, consisting of an acid 10 and an acid salt, capable of removing substantially all the ash forming material introduced into the solution with the hypochlorite and the acid, or acid salt.

5. The method of refining affinited sugar 15 which comprises substantially decolorizing the syrup made therefrom by means of a quantity of a hypochlorite sufficient to substantially decolorize the solution and a quantity of material of the group consisting of an acid and acid salt 20 capable of forming a salt substantially insoluble in the syrup with substantially all the metallic ion of the hypochlorite and the acid salts.

6. The method of refining affinited sugar 25 which comprises treating the syrup made therefrom with calcium hypochlorite and an acid phosphate in amount sufficient to substantially decolorize the solution and at a pH greater than 7, and, thereafter, crystallizing the sugar.

7. The method of decolorizing affinited sugar 30 which consists in treating the syrup made from the affinited sugar with calcium hypochlorite and an acid phosphate in amounts sufficient to substantially decolorize the solution.

8. The method of refining affinited sugar which 35 consists in decolorizing the syrup made from the affinited sugar with a quantity of a hypochlorite sufficient to substantially decolorize and a quantity of material of the group consisting of an acid or acid salt capable of removing substantially all the ash forming material introduced 40 into the syrup and thereafter dechlorinating the syrup.

9. The method of decolorizing affinited sugar which consists in treating the syrup made from 45 the affinited sugar with a quantity of a hypochlorite sufficient to substantially completely decolorize the solution.

10. The method of decolorizing affinited sugar which consists in treating the syrup made from 50 the affinited sugar with calcium hypochlorite and a water soluble calcium phosphate in amount sufficient to substantially completely decolorize the solution.

PEDRO SANCHEZ. 55

CERTIFICATE OF CORRECTION.

Patent No. 1,989,156.

January 29, 1935.

PEDRO SANCHEZ.

It is hereby certified that error appears in the printed specification of the above numbered patent requiring correction as follows: Page 3, first column, lines 56-57, claim 2, strike out the words "move to right at room temperature"; and that the said Letters Patent should be read with this correction therein that the same may conform to the record of the case in the Patent Office.

Signed and sealed this 19th day of March, A. D. 1935.

Leslie Frazer
